UNIVERSAL MOTION ACTUATOR

Alfred Richard Koch, Jr., Freeport, Ill., assignor, by mesne assignments, to Minneapolis-Honeywell Regulator Company, Minneapolis, Minn., a corporation of Delaware

Application October 15, 1949, Serial No. 121,581

12 Claims. (Cl. 74—1)

1

This invention relates to actuating mechanisms for actuator operated devices.

An important object of the invention is the provision of a switch actuator capable of actuating the switch in a uniform manner in response to movement of the operator in any of a multiplicity of directions approaching universal movement.

Another object of the invention is the provision of an actuating mechanism of the above character having novel means for converting tilting, rotative or axial movement of an operator into movement of a member engageable with an actuator to operate a device.

Another object of the invention is the provision of an actuating mechanism of the above character including an operator movable toward and away from an actuator on a device having novel means for converting the movement of the operator in either direction of movement into movement for actuating the device.

Another object of the invention is the provision of an actuating mechanism of the above character that is positive in its operation, that is readily attached to the device, that is easy to assemble, that is simple, that is rugged, and that is relatively inexpensive to manufacture.

Other objects and advantages of the invention will become apparent from the following detailed description taken in connection with the accompanying drawings, in which—

Figure 1 is an end elevational view of the actuating mechanism embodying the present invention mounted on a precision snap action switch;

Fig. 2 is a side elevation view of the actuating mechanism shown in Figure 1;

Fig. 3 is an opposite end view of the actuating mechanism shown in Figure 1;

Fig. 4 is a sectional view taken substantially along the line 4—4 of Figure 1 with portions of the switch housing shown in elevation;

Fig. 5 is a fragmentary sectional view similar to Fig. 4 showing the relation of the parts when an axial force is applied to the stem of the operator;

Fig. 6 is a fragmentary sectional view which shows the relation of the parts when the operator is rotated;

Fig. 7 is a fragmentary sectional view which shows the relation of the parts when the operator is moved or translated bodily in the direction of the longitudinal axis of the actuating mechanism;

Fig. 8 is a fragmentary sectional view showing

2

the relation of the parts when the operator is tilted, and

Fig. 9 is a fragmentary sectional view showing the relation of the parts when a pulling force is applied to the operator.

Referring now to the drawings the invention is shown embodied in an actuating mechanism for a plunger operated device such as a snap acting switch 11 actuated by an actuator comprising a plunger 12. In general the actuating mechanism is arranged to convert tilting, rotative or axial movement of an operator into longitudinal movement to move the plunger 12 in an operating movement of the switch 11. In this embodiment of the invention the actuating mechanism includes a pair of levers or arms 13 and 14, an operator 16 having a wedging portion disposed between the levers 13 and 14, and support means for mounting the levers 13 and 14 and the operator 16 on the switch 11 in a position to have one of the levers engage the plunger 12.

The support means shown includes a pair of spaced plates 17. The latter are disposed in side by side relation with opposite sides of the body of the switch 11 and are secured thereto as by bolts 18 or the like extending through the plates and the body of the switch 11. The lever 13, which is provided with upturned flanges 19 along its edges, is disposed between the plates 17 in spaced relation to the plunger 12 and is pivotally supported near one end on a pin 21 extending through the flanges 19 and through the support plates 17. Washers 22 may be disposed between the flanges 19 and the support plates 17 to minimize friction between the lever 13 and the support plates. The lever or arm 14, which is formed with downturned side flanges 23, is also disposed between the plates 17 and is in spaced side by side relation with the lever 13. At one end the arm 14 is formed with spaced upturned ears 24 shaped to be disposed between and in side by side relation with ears 26 extending downwardly from the side flanges 19 on the lever 13. A pin 27 extending through the ears 24 and 26 provides a pivotal mounting for the arm 14 on the end of the lever 13. A tongue 28 depressed out of the plane of the lever 14 may be provided to effect engagement between the lever 14 and the plunger 12.

The actuator 16 includes a spacer 28 and a stem 29, the spacer being disposed between the face of the lever 13 and the face of the arm 14 and the stem 29 projecting upwardly through an opening 31 in the lever 13 to be accessible on the upper side of the latter. The spacer 28 in the present

embodiment is circular in form and has faces 32 and 33 in engagement with the lever 13 and the arm 14 respectively so that upon tilting of the disc in any direction the arm 14 is forced or wedged away from the lever 13. The dimensions of the opening 31 and the stem 29 are such that the operator may be freely tilted, twisted or moved axially with respect to the lever 13 and arm 14. A downwardly extending projection 34 is formed on the disc 28 at one side of the longitudinal axis of the operator 16 receivable in a complementary recess 36 formed on the opposed face of the arm 14. The walls of the recess 36 are shaped so that when the operator 16 is twisted or rotated the projection 34 acts on the walls of the recess, urging the arm 14 away from the lever 13 to rotate the same about its pivotal support. In other words, the projection 34 and recess 36 form a cam means between the operator and the arm 14 and the lever 13 for urging the arm 14 away from the lever upon twisting movement of the operator to actuate the switch 11.

An abutment 37, in the form of a crosspiece supported at opposite ends by the support plates 17 at a position between the operator 16 and the pivotal connection between the lever 13 and the arm 14, acts as a stop and provides a fulcrum about which the arm 14 pivots when a pulling force is applied to the operator to move the operator axially away from engagement with the arm 14.

In this embodiment of the invention the precision snap switch 11 has a spring system 35 of the self-return type; that is, the spring system in the switch 11 is arranged so that when the operating pressure is released from the plunger 12 the spring system tends to return the plunger 12 to its initial position. Thus, through the effects of the spring system the arm 14 is urged to the position it assumes as shown in Fig. 4. It is to be understood however that a separate spring may be utilized to return the component parts of the actuating mechanism to a preselected given position in lieu of depending upon the spring system of the snap action switch.

The operation of the actuating mechanism is illustrated in Figs. 4-9. The arrows at the right hand side of the stem 29 of the operator indicates the direction of force applied to the operator 16.

In Figures 1 through 4 the lever 13, the arms 14 and the operator 16 are in their normal position, it being understood that the parts are biased to this position by the spring system in the switch 11. In this position of the parts the tongue 20 rests on the end of the plunger 12 and the disc 28 is disposed between the arm and lever so that the surface 32 of the disc abuts against the bottom of the lever 13 and the surface 33 of the disc abuts against the top of the arm 14 with the projection 34 disposed in the recess 36.

Fig. 5 shows the position of the parts when a force is applied to the operator 16 in a direction to move the operator axially toward the plunger 12. As pressure is applied to the operator the arm 14 pivots about the pin 27 and urges the plunger 12 axially to actuate the switch 11. Upon release of the force on the operator 16, the spring system in the switch 11 urges the operator 16 and the arm 14 to return to their normal position shown in Fig. 4.

Fig. 6 shows the relation of the parts when rotation is applied to the operator 16. Upon rotation of the operator the projection 34 bears against the side walls of the recess 36 forcing the arm 14 downwardly to press the tongue 20 against

35

the plunger 12 to operate the switch. Normally very little rotary motion of the operator 16 is required to effect actuation of the switch. The projection 34 does not clear the recess 36 so that upon release of the force, the projection 34 reseats in the recess 36. The spring system of the switch urges the plunger 12 and in turn the arm 14 to their original position shown in Fig. 4 so as to aid in the seating of the projection in the recess.

Fig. 7 shows the relation of the parts when an operating force is applied to the operator 16 in a direction at right angles to the longitudinal axis of the stem 29 to effect translation of the operator sufficient to operate the switch under such a force. The projection 34 moves relative to the side wall of the recess 36 and causes the arm 14 to be forced or wedged toward the switch as shown to depress the plunger 12 of the switch. Upon release of the force the parts assume their initial position shown in Fig. 4.

Fig. 8 shows the relation of the parts when the switch is operated in response to a force applied to the stem 29 in a direction to cause tilting thereof. While in Fig. 8 the tilting force is shown as being applied to the stem 29 in one radial direction it will be understood that the same action results when a similar force is applied at any point around the stem. This force causes an edge of the surface 33 to engage the arm 14 and a diametrically opposite edge of the surface 32 to engage the lever 13. As a consequence the arm 14 is urged or wedged away from the lever 13. By making the disc 28 circular the plunger is prevented from rotating when a tilting force is applied thereto. Upon release of the tilting force the parts return to their normal position.

Fig. 9 shows the relation of the parts when a pulling force is applied to the operator 16. As a pulling force is applied to the stem 29 the top surface 32 of the disc bearing against the lower surface of the lever 13 causes rotation thereof about its mounting pin 21. This raises the pivot pin 27 by which the arm 14 is mounted on the lever 13. Since the arm 14 normally engages the stop 37, such movement of the pivot pin 27 causes the arm 14 to rotate about the stop 37 as a center thereby moving the finger 20 toward the switch to depress the plunger 12 and operate the switch.

The invention provides relatively simple mechanical device capable of operating a switch or other mechanisms capable of operation by a similar type of movement wherein force can be applied to the stem in almost any direction and yet act to operate the mechanism. This provides great flexibility in the manner and position in which the switch or other device may be mounted with respect to the means from which the device is operated, a matter of considerable importance with the actuator and switch as used in safety devices.

I claim:

1. In a device of the character described, the combination of an operator, means for mounting said operator permitting rotative, tilting and axial movement thereof, a member shaped to engage an actuator of a device and movable between preselected positions to actuate the device, and lever means carried by said operator directly engaging said member for converting any of said above described movements of the operator into actuating movement of said member.
2. In an operating mechanism for a device

operated by an actuator, the combination of a pivotally mounted arm engageable with said actuator, an operator free to be rotated, tilted or moved toward said actuator, and cam means carried by said operator directly engaging said arm operable to convert any of said above described movements into movement of said arm to actuate the device.

3. In an operating mechanism for a device having an actuator, the combination of a pivotally mounted arm engageable with said actuator and movable between preselected positions to actuate said device, an operator mounted for rotary, tilting or axial movement relative to said actuator, and a cam carried by said operator to move therewith at one side of the line of movement thereof and a cam surface on said arm engaged by said cam to convert any of said above described movements into movement of said arm between said preselected positions.

4. In a mechanism for a device operated by an actuator, the combination of a first lever engageable with said actuator and movable between opposed positions to actuate said device, a second lever in spaced relation to said first lever and pivotally connected to said first lever, fixed means forming a pivotal support for said second lever, a wedging member disposed between said first and second levers tilttable in any direction and movable toward the actuator to move said first lever between said preselected positions, cam means acting between one of said levers and said wedging member operable to move said first lever between said preselected positions upon rotation of said wedging member, and means connected to said wedging member operable upon the application of force thereto to effect one of the above described movements of the wedging member.

5. The combination recited in claim 4 in which the wedging member is movable toward and away from the actuator and stop means is provided to be engageable by said first lever upon movement of the wedging member away from the actuator to effect movement of the first lever between said opposed positions.

6. In an actuating mechanism for a device operated by an actuator, the combination of an arm engageable with said actuator and having a recess formed on a side thereof away from said actuator, a lever in spaced relation to said arm and pivotally connected at one end to said arm, said lever having an aperture intermediate its ends, fixed means pivotally supporting the opposite end of the lever, a rigid member disposed between said arm and lever tilttable in any direction and movable in a direction toward the actuator to urge said arm away from the lever to move said actuator to operate the device, said rigid member having a projection shaped to be received in said recess on the arm and movable relative to the recess to urge said arm away from said lever to move said actuator to operate the device upon rotation of the rigid member, and means secured to said rigid member extending through said aperture in the lever operable upon application of force thereto to effect one of the above described movements of the rigid member.

7. In an actuating mechanism for a device operated by an actuator, the combination of a mounting plate shaped to be attached to the side of said device, a first lever engageable at one end with said actuator, a second lever in spaced side by side relation to said first lever and pivotally

supporting the opposite end thereof, means for pivotally supporting said second lever on said plate, a rigid wedging member disposed between said first and second levers and free to be tilted in any direction to urge the first lever to move said actuator to operate said device, cam means acting between one of said levers and the rigid wedging member operable upon rotation of said rigid wedging member to urge the first lever to move said actuator to operate said device, and a stem rigid with said wedging member and projecting through one of said levers and operable upon application of force thereto to effect one of the above described movements of the wedging member.

8. In an actuating mechanism for a device operated by an actuator, the combination of spaced mounting plates, means for detachably securing said plates to opposite sides of said device, a lever disposed between said plates in spaced relation to said actuating member, means for pivotally mounting one end of said lever on said plates to have the opposite end movable between opposed positions, an arm in spaced relation to said lever between said device and said lever and engageable at one end with said actuator, means for pivotally supporting the opposite end of the arm on said opposite end of the lever, an operator including a portion disposed between said lever and said arm tilttable in any direction, rotatable about an axis and movable axially toward or away from the arm to move the arm to actuate the device, and a second portion arranged to be accessible and operable upon application of force thereto to effect one of the above described movements of the first portion.

9. In an actuating mechanism for a device operated by an actuator, the combination of a support shaped to be attached to the device, a first lever in spaced relation to said actuator pivotally mounted on said support, a second lever disposed between the first lever and the actuator pivotally supported on the first lever, said second lever being movable between opposed positions and engageable with the actuator to actuate the device, a wedging member disposed between said first and second levers tilttable in any direction and movable toward the actuator to move said second lever between preselected positions, cam means acting between one of said levers and said wedging member operable to move said second lever between said preselected positions upon rotation of said wedging member, and means operable upon the application of force thereto to effect one of the above described movements of the wedging member.

10. The combination recited in claim 9 in which the wedging member is movable axially toward and away from the actuator with an abutment mounted on the support extending between the levers at a position between the actuator and the pivotal connection between the levers whereby upon movement of the wedging member away from the actuator the second lever engages the abutment and rotates thereabout to move the actuator to actuate the device.

11. In an actuating mechanism for a device operated by an actuator, the combination of a support, means for detachably securing the support to said device, a lever in spaced relation to said actuating member, means for pivotally mounting one end of said lever on said support to have the opposite end movable between opposed positions, an arm in spaced relation to said lever between said device and said lever and

engageable at one end with said actuator, means for pivotally supporting the opposite end of the arm on said opposite end of the lever, an operator including a portion disposed between said lever and said arm tilttable in any direction, rotatable about an axis, movable axially toward or away from the arm and movable transaxially to move the arm to actuate the device, and a second portion arranged to be accessible and operable upon application of force thereto to effect one of the above described movements of the first portion.

12. In a mechanism for a device operated by an actuator, the combination of a first lever engageable with said actuator and movable between opposed positions to actuate said device, a second lever in spaced relation to said first lever and pivotally connected to said first lever, fixed means forming a pivotal support for said second lever, a first stop limiting pivotal movement of said second lever toward said actuator, a second stop engaging said first lever intermediate its pivotal connection to said second lever and said

actuator to cause said first lever to move said actuator on movement of said second lever in one direction abouts its pivotal support, a wedging member disposed between said first and second levers tilttable in any direction and movable toward and away from said actuator to move said first lever between said pre-selected positions, and means connected to said wedging member operable upon the application of force thereto to effect one of the above described movements of said wedging member.
